UNITED STATES PATENT OFFICE.

ROBERT C. MATHES, OF NEW YORK, N. Y., ASSIGNOR TO WESTERN ELECTRIC COMPANY, INCORPORATED, OF NEW YORK, N. Y., A CORPORATION OF NEW YORK.

REPEATER SYSTEM.

Substitute for application Serial No. 230,978, filed April 26, 1918. This application filed April 5, 1921.
Serial No. 458,857.

To all whom it may concern:

Be it known that I, ROBERT C. MATHES, a citizen of the United States, residing at New York, in the county of Bronx, State of New York, have invented certain new and useful Improvements in Repeater Systems, of which the following is a full, clear, concise, and exact description:

This application is a substitute for the applicant's case Serial Number 230,978 filed April 26, 1918, which has become abandoned.

The invention relates to repeater systems wherein relatively weak currents arriving at a repeating station are to be repeated and sent out upon the line in amplified form. Such systems may be employed for amplifying telephone currents, ringing currents or the like.

Repeater systems have been proposed in which a one-way repeater is adapted for the two-way transmission of current by reversing the connections of the repeater to the line. This reversal has been accomplished automatically by means of a relay for each line and responsive to the current impressed on the line. The repeater is connected to transmit in one direction or the other through the line, depending upon which of the two relays is energized.

An object of the present invention is to simplify circuits of this type and to this end the invention provides a repeating system wherein but a single relay responsive to the actuating current is employed for reversibly connecting the repeater. The repeater is normally connected to transmit current in one direction between the lines. If incoming current finds the repeater properly connected no change is made in the connections.

If the repeater is not in a condition to repeat the incoming current the relay is actuated, which not only reverses the repeater connections but also transfers the control of the relay to the other line. The repeater and the relay are connected in conjugate relation to the line so that the relay will be actuated only by incoming current and not by outgoing current. This insures that after the relay has been transferred from the incoming to the outgoing line, the relay will be unaffected by the outgoing currents and will only be actuated by incoming currents, provided the repeater is properly connected.

For further details of the invention reference may be had to the drawings, in which Fig. 1 illustrates diagrammatically one embodiment of the invention; and Fig. 2 shows the direction of the magnetic flux produced by the winding of relay 7.

Referring to Fig. 1 of the drawings, the lines 1 and 2 have provided therebetween an amplifier or repeater 3 which is adapted to be reversibly connected to the lines by means of the electromagnetic switches 4 and 5. The repeater 3 is here shown of the mechanical type but may be of the vacuum tube type if desired. The alternating current relay 6 responds to current impressed on one or the other of the lines to operate the polarized relay 7, which operates the reversing switches 4 and 5 as well as the relay 8, the latter disconnecting the relay 6 from one of the lines and connecting it to the other.

Current is supplied at times to the switches 4 and 5 and to relay 8 by battery 21 in circuit with which is contact 22 on armature 16 of polarized relay 7. With armature 16 in the position shown the battery 21 is disconnected and in its alternate position it is connected to the switches 4 and 5 and relay 8. The armature 16 is polarized and its movement is controlled by vibrating contact 9 through the intermediary of the windings 10, 11, 12 and 13 and the batteries 14 and 15. The armature 16 carries a contact 17, which, with armature 16 in the position shown, closes a circuit through armature 16 and the four windings 10-13 to battery 15. The contact 9 is in series at all times with the windings 10 and 11.

If relay 6 is not energized, its contact 9 is closed and battery 15 supplies current to windings 10-13 which are wound in such a direction that the fluxes produced by windings 10 and 11 neutralize the fluxes produced by windings 12 and 13. In this condition the resultant effect of the windings 10-13 is zero and the armature 16 remains in the position shown uninfluenced by current through the windings of relay 7. The relative direction of the fluxes produced by the windings of relay 7 are shown by the arrows in Fig. 2. When the circuit of windings 10 and 11 is opened by the vibration of contact 9 or otherwise, the windings 12 and 13 are effective to move armature 16 to the left. Armature 16 moves sluggishly as com-

pared to contact 9 so that with contact 9 vibrating, due to current coming in over line 2, and armature 16 having moved to the left, contact 22 will effect the energization of relay 8, thereby disconnecting relay 6 from line 2 which deenergizes relay 6 and closes contact 9 before contact 17 permits reverse current from battery 14 through windings 12 and 13 to move armature 16 to the position shown. With line 2 as the incoming line, the armature 16 will be moved to and remain to the left so that contact 22 will energize switches 4 and 5, thereby connecting the input side of the repeater to line 2, 16 its output side to line 1.

Relay 6, when connected by relay 8 and repeating coil 19 to the line 1, is not operated by outgoing currents in line 1 because the repeater connections 24 and the line 26 leading to relay 6 are connected in conjugate relation to the line 1 and the artificial line 23. Outgoing currents in line 2 likewise do not operate the relay 6 when the latter is connected to line 2, the repeating coil 25 18 and artificial line 20 corresponding to the elements 19 and 23, respectively, associated with line 1. After line 2 has been the incoming line, until line 1 becomes the incoming line, relays 4, 5 and 8 will remain 30 energized, relay 6 will remain deenergized, contact 9 will remain closed, and armature 16 will remain to the left, since current flows from battery 14 through coils 10, 11, 12 and 13, through contacts 17, and back to battery 14, the effects of coils 10 and 11 neutralizing the effects of coils 12 and 13. Then, when line 1 becomes the incoming line, relay 6 opens contact 9, thereby deenergizing coils 10 and 11, whereupon coils 12 and 40 13, fed from battery 14, move armature 16 to the right. Since, as noted above, armature 16 is sluggish as compared to contact 9, the latter closes before current from battery 15, flowing in coils 12 and 13, can 45 move armature 16 back to the left. Thus the circuit through the coils of relays 4, 5 and 8, which was broken at 22 when armature 16 moved to the right, remains open at 22. In fact, all of the switches remain 50 as shown in the drawing until line 2 becomes the incoming line.

With the armatures of the relay 8 in the positions shown in the drawing, the relay 6 is operatively connected by means of the repeating coil 18 to the line 2. With the armatures of relay 8 in their alternate positions the relay 6 is operatively connected by means of the repeating coil 19 to the line 1. For currents coming in over the line 60 1, with the connections as shown, the incoming currents are supplied to the open contacts of the relay 8 and the operation of the relay 6 is prevented. This is desired, for the incoming currents find the 65 switches 4 and 5 in proper positions to

repeat current from the line 1 to the line 2. Outgoing current from the line 2 is not supplied by repeating coil 18 back to the relay 6, as described above. If current comes in over the line 2 it is necessary to 70 reverse the connections of the repeater in order to repeat these currents to the line 1. This is done as follows: The incoming currents are transferred by means of repeating coil 18 to the relay 6, which vibrates its 75 armature 9 and moves armature 16 of relay 7 to its alternate position, thereby connecting battery 21 by way of ground and the insulated contact 22 of armature 16 to the solenoids of relays 4, 5 and 8 to ground. The 80 energization of relay 8 disconnects the relay 6 from line 2 and connects the relay 6 to the line 1. The energization of switches 4 and 5 reverses the connection of the repeater 3 so that the input side of the same 85 is connected to the line 2 and the output side thereof to the line 1, as required.

The above description is based on the assumption that a very close balance may be maintained between lines 1 and 2 and their artificial lines 23 and 20. In actual practice, however, considerable unbalance can be taken care of by placing the apparatus at separate stations; actual line 1, repeater 19 and artificial line 23 being located at one 95 station, represented in the drawing at A; the other line 2, repeater 18 and artificial line 20 being remote from station A at station C; repeater 3, together with relay 6 and its associated apparatus being remote from 100 stations A and C and located at an intermediate station B. In actual practice the distance from station B to either of the stations A or C would be a matter of miles, perhaps ten to fifteen standard cable miles. 105

As above indicated the relay 6 is to be operated only by incoming currents and not by outgoing currents and this is secured in the following way by placing the apparatus at different stations as described. Assume 110 that line 1 is an incoming line and that repeater 3 compensates for the attenuation in the line 24. The current at the output side of the repeater will then have practically the same intensity as the current transferred by 115 repeating coil 19 to line 26. Current coming in over the line 1 must be transferred to relay 6 with sufficient intensity to operate that relay unless the repeater is already 120 properly connected. It is obvious that this incoming current is subjected to the attenuation of the line 26. Current which leaves the output side of the repeater should all be sent out upon the line 2, but due to the assumed unbalance between the line 2 and the artificial line 20, a small fraction of current arriving at the repeating coil 18 will be transferred to the line 27. If the line 25 is approximately as long as 125 the line 26, then the current from the 130

output side of the repeater arriving at the input side of repeating coil 18 will have practically the same amplitude as the incoming currents supplied to the relay 6 by way of line 26. Only a very small fraction of the outgoing currents is transferred from line 2 to the line 27, and this relatively small fraction is subjected to the attenuation of the line 27, so that the unbalanced outgoing currents which are supplied to the relay 6 by way of line 27 are very small in amplitude in comparison to the incoming currents which are supplied to the relay 6 by way of the line 26. The difference in amplitude of these two currents is sufficiently large to maintain a proper factor of safety whereby the relay 6 will respond to the relatively strong incoming current as desired but not to the relatively weak fraction of outgoing current which may come back over line 27. This factor of safety obtains, of course, also in the case where line 2 is an incoming line and line 1 an outgoing line.

What is claimed is:

1. The combination of a telephone line, a balancing line therefor, a repeater for said line, and an alternating current relay for controlling said repeater, said repeater comprising terminals, and said relay and said terminals being associated in conjugate relation to said lines.

2. The combination of two telephone lines, an artificial line for each of said lines, a repeater for said lines, and a relay controlling said repeater, said repeater and said relay being associated in conjugate relation to each of said telephone lines and its corresponding artificial line.

3. The combination of two lines, a repeater, means for connecting said repeater to said lines, a relay for controlling said means, and means for connecting said relay to one of said lines while the latter is supplying outgoing currents and for rendering said relay unresponsive to said outgoing currents.

4. A two-way repeating system comprising two actual lines and their corresponding artificial lines, a repeater adapted to be

reversibly connected between said lines and a relay adapted to control the repeater connections, said relay and said repeater being connected in conjugate relation to each of said actual lines and their corresponding artificial lines.

5. A two-way repeating system comprising two actual lines and their corresponding artificial lines, a repeater adapted to be reversibly connected between said lines, a relay adapted to control said repeater, said relay and said repeater being connected in conjugate relation to each of said actual lines and their corresponding artificial lines, one of said actual lines and its artificial line being located at a station remote from another station at which the other actual and artificial lines are located, said repeater and said relay being between said two stations and remote therefrom.

6. A line, a repeater, a relay for controlling the connections of said line to said repeater, said relay having a vibratile contact, and means comprising said contact and responsive to current impressed on said lines for connecting said relay to the output circuit of said repeater.

7. A two-way repeater system comprising two lines, a repeater adapted to be reversibly connected thereto, and means comprising a single voice operated relay device for reversing the repeater connections for transmission in either direction between said lines.

8. A two-way repeating system comprising a line, a unidirectionally transmitting repeater, means operable to reverse the pointing of said repeater in said line, and means responsive to alternating current energy approaching the repeater from the direction toward which it is pointed for causing said first mentioned means to initiate reversal of the pointing of the repeater while it is transmitting, provided said energy is of sufficient magnitude.

In witness whereof, I hereunto subscribe my name this 21 day of March A. D., 1921.

ROBERT C. MATHES.
